(57) **CLAIM**

The ornamental design for a combined electrical outlet box with hanger bars as shown and described.

DESCRIPTION

FIG. 1 is a left, front, bottom perspective view of a combined electrical outlet box with hanger bars;

FIG. 2 is a left side perspective view thereof;

FIG. 3 is a right side, rear, bottom perspective view thereof;

FIG. 4 is a left side, front, bottom perspective view thereof;

FIG. 5 is a left side, front, top perspective view thereof;

FIG. 6 is an exploded perspective view thereof;

FIG. 7 is a top view thereof;

FIG. 8 is a right side view thereof;

FIG. 9 is a rear view thereof;

FIG. 10 is a front view thereof;

FIG. 11 is a bottom view thereof; and,

FIG. 12 is a left side view thereof.

In the drawings, the broken lines are for the purpose of illustrating portions of the combined electrical outlet box with hanger bars that forms no part of the claimed design.
